UNITED STATES PATENT OFFICE.

WILLIAM M. VENABLE, OF PITTSBURGH, PENNSYLVANIA, ASSIGNEE TO BLAW STEEL CONSTRUCTION COMPANY, OF PITTSBURGH, PENNSYLVANIA, A CORPORATION OF NEW JERSEY.

COLUMN-TOP MOLD.

1,129,145.

Specification of Letters Patent. Patented Feb. 23, 1915.

Application filed October 9, 1912. Serial No. 724,725.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Column-Top Molds, of which the following is a specification.

The invention relates to molds or forms for molding the tops of concrete columns, and has for its primary objects; the provision of a column top mold having a plurality of sides which can be readily adjusted for columns of varying diameter; the provision of a column mold having a plurality of sides in which the bottom diameter of the form may be adjusted without varying the top diameter, and in which the form remains symmetrical through all its various adjustments; the provision of a column top which can be cheaply and easily constructed from sheet metal and which shall be of very rigid form when assembled; the provision of a column top mold presenting a smooth interior adapted to form a surface free from marks due to fastenings; and the provision of improved connecting means for use between the column top form and the cylindrical form for the body of the column. Certain embodiments of the invention are illustrated in the accompanying drawings, wherein—

Figure 1 is a vertical two-part section through my improved mold or form, one half of the section showing the mold expanded to its largest size, and the other half of the section showing the mold reduced to its smallest size; Fig. 2 is a two-part plan view of the structure shown in Fig. 1; Fig. 3 is a plan view of one of the plates employed, before such plate has been bent to the form in which it is used; Fig. 4 is an edge view of the plate of Fig. 3; Figs. 5 and 6 are plan and edge views respectively of the plate of Fig. 3 after it has been bent to the form in which it is used in the mold; Fig. 7 is a section on the line VII—VII of Fig. 5; Fig. 8 is a plan view of the connecting ring employed, and Fig. 9 is a side elevation of one of the halves of the connecting ring shown in Fig. 8.

Briefly stated, the mold consists of a plurality of similar tapering sheet metal plates each having one of its side edges bent backward to form a securing flange, and the

other side edge overlapping the flange of the adjoining plate, a plurality of rows of holes being provided in the edges of the plate not having the flanges, so that an adjustment as to size may be secured. The lower end of the form thus constructed is secured detachably to the top of a column form by means of a collar, while the upper portion of the mold is finished off by means of another collar of fixed diameter and having its sides formed to fit the series of plates constituting the mold. By the use of this upper collar the top diameter of the mold is maintained constant, such collar being shifted up and down as the plates are adjusted in or out, in order to vary the size of the lower end of the mold.

Referring to Figs. 1 and 2, which views show on one side the mold adjusted to its largest diameter, and on the other side the mold adjusted to its smallest diameter, 1, 1, 1, etc. are the plates from which the body of the mold is built up; 2 is the bottom collar serving to connect the body of the mold with the upper end of a cylindrical column mold 3; 4 is the top or other collar of fixed diameter secured to the upper interior surface of the body of the mold, and 5 is the flooring into which the upper edge of the collar 4 fits. As illustrated in Figs. 1 and 2, the mold is constructed with eight plates, thus forming an eight sides top, but it will be understood that the number of sides may be varied without departing from the invention.

Figs. 3 and 4 illustrate one of the plates 1 as it is cut out, but before being bent into the form in which it is used in the mold. The plate is provided adjacent one edge with the single row of holes 6, and adjacent the other edge with the plurality of rows of holes 7, 8, 9, and 10, the number of rows of holes depending upon the number of adjustments desired. The upper edge of the plate is also provided with a series of rows of holes 11, 12, 13, and 14, to provide for the vertical adjustment of the collar 4 to correspond with the other adjustments of the various plates. In order to form the plate of Figs. 3 and 4 into the shape in which it is to be used, it is bent along the dotted lines 15 and 16 to form the flanges 17 and 18, as indicated in Figs. 5, 6, and 7, the body of the plates also being bent to the contour as indicated in Fig. 6. By ref.

erence to Figs. 1 and 2 it will be seen that when the plates are assembled the flange 17 on one plate overlaps the edge of the next plate, and that the parts are secured together by means of ordinary stove bolts 19. By shifting the flanges 17 so that the holes therein register with the various rows of holes 7, 8, 9, and 10, the diameter of the mold at its lower end may be adjusted to correspond with various diameters of columns, the range of adjustment being apparent from an inspection of Figs. 1 and 2 in which one half of the mold is shown adjusted to its largest diameter and the other half of the mold adjusted to its least diameter.

The collar 4 which completes the upper portion of the mold is made preferably of sheet metal, and is provided at its lower edge with a flange 20 for engaging the interior surfaces of the plates 1, and at its upper edge is provided with an angle 21 for bearing against the under surface of the flooring 5. This collar 4 remains always the same in size regardless of the adjustments of the plates 1, as will be readily understood from an inspection of Fig. 1. To compensate for the changes in the inward diameter of the portion of the mold formed by the plates 1, however, the collar must be moved vertically along the interior surface of the form as the plates 1 are adjusted. This vertical adjustment of the collar 4 upon the interior surface of the plate 1 is provided for by means of the series of holes 11, 12, 13, and 14. The collar is preferably held in any desired position of adjustment by means of the stove bolts 22 which pass through the perforations in the flange of the collar and in the plates 1. It will be seen that by this arrangement the top diameter of the column head as measured at the collar 4 always remains the same, while the lower diameter may be varied to suit the diameter of column with which the column head is used. It will also be seen that the portions of the plates in use in their various positions of adjustment always remain symmetrical, that the surface presented by the inside of the form is smooth, and that

the securing means between the overlapping flanges are readily accessible in the operation of assembling and disassembling the parts.

As indicated in Figs. 8 and 9, the ring 2 for use at the bottom of the mold is made in two sections held together by means of the bolts 23, thus clamping ring or collar over the upper end 3 of the column mold. The upper edge 24 of the collar is secured to the flange 18 at the bottom of the plates 1, by means of bolts (not shown). As indicated in Fig. 8, the upper interior portion of the ring 2 is shaped to conform in configuration with the interior shape of the lower end of the column head mold, while the lower interior portion of the ring is cylindrical to fit the cylindrical upper end of the column mold 3. The method of operating the mold and the advantages incident thereto will be readily apparent to those skilled in the art. When the cross section of the column with which the column top is to be used is not round, but is angular and corresponds in the number of sides with the number of sides of the column top, the transition ring or collar 2 is of course unnecessary.

Having thus described my invention and illustrated its use, what I claim as new and desire to secure by Letters Patent, is the following.

In combination in a column head mold, a plurality of similar tapering plates each having one side edge bent backward at an angle to form a securing flange and provided with holes, and having the other side edge lying in the plane of the body of the plate and overlapping the side edge of the adjoining plate, the said other side edge of each plate having a plurality of sets of holes arranged in rows paralleling the edge, and securing means adapted to extend through the said holes.

In testimony whereof I have hereunto signed my name in the presence of the two subscribed witnesses.

WILLIAM M. VENABLE.
